(57) **CLAIM**

The ornamental design for a hanging light, as shown and described.

DESCRIPTION

FIG. 1 is a first perspective view of a hanging light design showing my new design;

FIG. 2 is a second perspective view of a hanging light;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion “9” in FIG.1; and,

FIG. 10 is an enlarged view of the selected portion “10” in FIG.2.

Any shading and cross-hatching are not features of the design but are utilized to illustrate the surface contours of the hanging light design in the drawings.
